Patented May 7, 1918.

UNITED STATES PATENT OFFICE.

SAMUEL G. CONKLING, OF SAUGERTIES, NEW YORK, ASSIGNOR OF ONE-HALF TO LOUIS SCHAFFERT, OF BROOKLYN, NEW YORK.

TRAIN SAFETY DEVICE.

1,265,615.

Specification of Letters Patent.

Patented May 7, 1918.

Application filed July 24, 1913. Serial No. 780,858.

To all whom it may concern:

Be it known that I, SAMUEL G. CONKLING, a citizen of the United States, residing in Saugerties, in the county of Ulster and State of New York, have invented certain new and useful Improvements in Train Safety Devices, of which the following is a specification.

My invention relates to a train safety device, by means of which the motive power is shut off and the air brakes automatically applied, independent of the engineer, when the train runs into a closed block.

One of the objects of my invention is to provide a simple inexpensive and positively actuating device of the above indicated character, which will be set into operative position or moved into inoperative position by the actuation of the usual semaphore signal and which can be installed in connection with either the usual pneumatically controlled brake applying or brake releasing mechanism now in general use.

The various other objects of the invention will be in part obvious and in part more fully set forth in the following description of a physical embodiment of my invention, which also discloses various new and novel features of construction and combination of parts hereinafter set forth and claimed.

Referring to the drawings:

Figure 1 is a side elevation of a locomotive and tender with part of the cab broken away to show a preferred embodiment of my invention installed therein;

Fig. 2 is a partly diagrammatic view of a modified form of the device from that shown in Fig. 1; and

Fig. 3 is an enlarged view of the trip valve shown in Fig. 2.

There is shown in the drawings a section of track 1 mounted between the rails 2 of which and on top of one of the ties 3 is a pair of transversely spaced apart bracket plates 4 pivotally mounted between which is an L-shaped track detent comprising an upstanding valve-engaging arm 6, the trip being pivoted to permit the arm 6 to move in one direction from its vertical to a horizontal position paralleling the tracks.

The invention has been illustrated with reference to an engine and its tender, due to the fact that the wheel brakes are usually applied to the engine wheels by the introduction of compressed air to the brake actu-

ating cylinder while in the tender, and in the other cars of the train, the brakes are normally in braking position and are moved to inoperative position by the introduction of compressed air to the brake releasing mechanism, but it is to be understood that this disclosure is merely illustrative and the invention may be utilized with obvious mechanical variations in either system of brake controlling mechanisms.

There is shown in Fig. 1, an engine 20 within the cab of which is mounted the usual reverse lever 21, steam or other motive control lever 22 and automatically controlled air-pressure pump 23, all as is usual in steam engines of this character, now in general use.

Air pressure from the pump 23 is supplied to a storage reservoir 24 leading from which is a piping 25 controlled by the two-way manually-controlled valve 26, the actuation of the handle of which in one direction permits the compressed air to pass through the pipe 25, through the branch 27, then through two pipes, one, the pipe 28, which leads to the cylinder 29 and which controls the application of the brakes 30 on the locomotive and also from the branch 27 through the pipe 31 to the similarly operated cylinder 32, which controls the application of the brakes 33 on the tender or on the cars in the train. Moving the handle of the valve 26 in the opposite direction, closes communication with the reservoir 24 and exhausts the pressure from the cylinders 29 and 32 through the outlet 34. Also leading from the cylinder 24 is a pipe 35 normally closed by the valve 46, which valve has a depending trip 48 normally positioned so that it will engage with the arm 6 when the same is in its upstanding position, but this handle is of such a length that it will pass over the foot 7 hereinbefore referred to when the block is open.

The pipe 35 leads to a cylinder 371, the piston rod 38 of which is connected by means of a few links of chain 39 to the motive power controlling lever 22. The air pressure in the cylinder 371 may be released by any suitable means such as a hand controlled releasing valve 40 so that the piston 38 may be drawn out to permit the free manual actuation of the lever 22. Leading from the pipe 35 between the valve 36 and the cylinder 371 and through the one-way valve 41 is a connection leading through the

branch 27 to the pipe 31 and to the pipe 28. From the reservoir 24 is a train pipe 42 leading to the cylinder 32 in the tender or cars, disposed within which pipe is a valve 43 similar to the valve 36 hereinbefore described.

Referring to the modification shown in Figs. 2 and 3, the cylinder 32 is maintained in non-braking position by air pressure in the cylinder which pressure may be released either manually by the engineer or by the movement of the train into a closed block. As shown the reservoir 24 has leading therefrom the pipe 25 which passes through the normally open passageway 45 in the three-way cylindrical valve 46, the axially disposed stem 47 of which has a depending handle 48 affixed to its outer end which handle is similar to the trip 37 and is also positioned to be engaged by the upstanding arm 6 at the entrance to a closed block. The pipe 25 on the opposite side of the valve 46 leads through a T 49 to the pipe 31, which pipe is also continuous through the T 49 and is adapted, when the trip 48 is rocked, to communicate through a normally closed passageway 50 in the valve 46 to an exhaust 51.

Leading from the cylinder 24 and through another normally closed passageway 54 in the valve 46 is the pipe 35 which leads to the cylinder controlling the motive control lever 22 as has been described with reference to Fig. 1. Leading from the cylinder 32, in this modification, is an outlet pipe 55 controlled by a valve 36 as hereinbefore described.

In operation with the parts in the position indicated in the drawings and the succeeding blocks "open," the engineer has full control of the motive power as the lever 22 can be moved back and forth without interfering with the piston rod 38, as the links of chain 39 permit a free movement of the lever 22. By means of the valve 26 shown in Fig. 1 or the valve 52 in the modified form shown in Fig. 2, the engineer has full control of the brake actuating mechanism as is common with locomotives now in general use. The trips 37 and 48 are normally in the depending position shown in the drawing, which in the disclosure shown in Fig. 1 normally maintain the pipe 35 and 42 closed and in the modifications shown in Figs. 2 and 3 normally maintaining an open communication in the pipe 25 so that the air pressure will be normally maintained in the cylinder 32 to maintain the brakes in inoperative position while the train is running. With the valves in the position indicated, should the train carrying the device shown in Fig. 1 run into a closed block, the engagement of the arm 6 with the trip 37 on the locomotive, would open the valve 46 admitting air pressure into the cylinder

371 which would act upon the rod 38 to draw the lever 22 toward the cylinder thus shutting off the steam or other motive power and at the same time, the air would pass the one-way valve 41 into the pipe 28 and cylinder 29 to apply the locomotive brakes 30 and at the same time the air pressure is admitted into the pipe 31 to actuate the cylinder 32 and thereby apply the brakes 33 on the tender, or other cars of the train. 75

Any continued movement of the train into the closed block would cause the handles in the succeeding cars to be engaged by the arm 6 thus opening communication between the cylinders 32 throughout the train and the reservoir 24 through the train pipe 42. Further should the detent be moved into position after the engine has passed, some one of the car trips would be operated.

Referring to the operation of the modified form of device shown in Figs. 2 and 3 the tripping of the handle 48 by the upstanding arm 6 closes communication through the passageway 45 thus shutting off the supply of compressed air through the pipes 25 and 31 and at the same time opening the pipe 31 to the exhaust 51 through the passageway 50. This releasing of air pressure in the cylinder 32 of Fig. 2 permits the mechanical application of the brakes as is usual in the cars. This tripping of the handle 48 also opens communication through the pipe 35 and through the passageway 54, thus introducing air pressure into the cylinder 371, to actuate the lever 22 as hereinbefore described. 100

Although I have shown only one form of mechanism embodying my invention, it is obvious that various changes within the skill of the mechanic may be made therein without departing from the spirit of the invention, provided the means set forth in the following claims are employed.

Having thus described my invention, I claim:— 110

1. In a means for automatically stopping a train when running into a closed block, the combination with a detent fixed adjacent the track, of a valve carried by the train positioned relatively close to the road bed, said valve having three pipes leading transversely therethrough, one of said pipes leading from a brake releasing cylinder to an exhaust, a second pipe leading from a source of compressed air to said first mentioned pipe and the third pipe leading from the source to a motive power shut off cylinder, a valve plug for said valve having three passageways therethrough, one of said passageways in one position of the plug maintaining open communication through said second mentioned pipe and closing communication through the other two pipes and a relatively short trip affixed to and normally depending from said plug adapted to be engaged by 130

said detent to close said second mentioned pipe and simultaneously to open communication through the other two pipes.

2. In a device of the class described, the system comprising a compressed air reservoir, a two way manually actuated valve, a cylinder open to said reservoir when the valve is in one of its two positions and open to the outside air when in its other position, a second cylinder, a pipe connecting said second cylinder with said reservoir when the valve is in its said other position, an exhaust from said second cylinder, a track detent controlled valve normally closing communication between said second cylinder and its exhaust and adapted to be moved to close communication between said reservoir and said second cylinder and simultaneously to open said second cylinder to its exhaust.

3. In a device of the class described, the system comprising a compressed air reservoir, a two way manually actuated valve, a cylinder open to said reservoir when the valve is in one of its two positions and open to the outside air when in its other position, a second cylinder, a pipe connecting said second cylinder with said reservoir when the valve is in its said other position, an exhaust from said second cylinder, a track detent controlled valve normally closing communication between said second cylinder and its exhaust and adapted to be moved to close communication between said reservoir and said second cylinder and simultaneously to

open said second cylinder to its exhaust, a third cylinder, a pipe connecting said reservoir with said third cylinder, said detent controlled valve being contained in said last named pipe and normally closing communication between said third cylinder and said reservoir and adapted to open said communication when said valve is moved.

4. In a device of the class described, the system comprising a compressed air reservoir, a cylinder, a pipe connecting said reservoir and said cylinder, a manually actuated two way valve in said pipe adapted in one position to open said reservoir to said cylinder and in the other position to open said cylinder to the outside, a second cylinder, a pipe leading from said reservoir to said second cylinder, a normally closed valve in said second named pipe adapted to be actuated by a track detent, a third pipe leading from said second named pipe between the normally closed valve and the second cylinder to the first named pipe between the two way valve and the first named cylinder whereby communication will be established between both of said cylinders and said reservoir by the opening of the normally closed track detent valve irrespective of the position of the manually controlled valve.

In witness whereof I have hereunto set my hand in the presence of two witnesses.

SAMUEL G. CONKLING.
